OIL BURNER

Filed Feb. 4, 1922

2 Sheets-Sheet 2

UNITED STATES PATENT OFFICE.

ARTHUR H. BALLARD, OF BOSTON, MASSACHUSETTS.

OIL BURNER.

Application filed February 4, 1922. Serial No. 534,061.

To all whom it may concern:

Be it known that I, ARTHUR H. BALLARD, a citizen of the United States, and a resident of Boston, county of Suffolk, Commonwealth of Massachusetts, have invented an Improvement in Oil Burners, of which the following description, in connection with the accompanying drawings, is a specification, like characters on the drawings representing like parts.

This invention relates to oil burners and consists more particularly in improvements in oil burners of the rotary type.

The invention will be best understood by reference to the following description taken in connection with the accompanying illustration of one specific embodiment thereof, while its scope will be more particularly pointed out in the appended claims.

20 In the drawings,—

Fig. 1 is an elevation partly in longitudinal section showing a burner embodying one form of the invention;

25 Fig. 2 is a cross-sectional elevation on an enlarged scale taken on the line 2—2 in Fig. 1;

Fig. 3 is a side elevation on an enlarged scale in partial section showing one form of automatic fuel controlled valve;

30 Fig. 4 is a sectional elevation of some of the parts illustrated in Fig. 3 and showing the fingers of a centrifugal device moved radially outward.

Fig. 5 is a plan view showing connections 35 between some of the valve controlling parts; and

Fig. 6 shows the parts of a centrifugal device with the fingers moved inwardly to the position they assume when the motor is 40 at rest.

Referring to the drawings and to the embodiment of the invention therein disclosed, I have there illustrated the same as applied to a rotary burner of the general class illustrated in my prior Patent No. 1,294,026, dated February 11, 1919, but it is to be understood that the invention as to many of its features may have useful application to widely different types of apparatus.

In the form of burner illustrated, the oil or other fuel is delivered to a rapidly rotating nozzle, herein in the form of a cup or sleeve 7, having an open mouth from 55 which the oil is discharged by centrifugal

action, the oil on leaving the mouth of the nozzle being further atomized by the action of an annular column of air delivered by a stationary annular air nozzle 9 surrounding the oil nozzle, but preferably separated therefrom by an intervening sleeve or partition 11, so as to prevent the cooling effect of the air on the oil or other fuel and to permit the preheating of the latter by heat radiated from the combustion chamber. 65

The mouth piece of the nozzle 7 is preferably thickened so as to extend the delivery edge of the nozzle laterally approximately to the outer periphery of the partition 11, which latter terminates just within said 70 thickened portion. The air nozzle 9 preferably extends beyond the end of said partition 11 to conduct the air directly against the fuel delivery edge of said nozzle.

To rotate the oil delivery nozzle or cup, 75 the latter has a hub 13 which has threaded attachment to the end of a main drive shaft 15, the latter being preferably journaled in ball bearings 17 and 19, and having at its opposite end a flexible coupling 21, by means 80 of which it may be driven directly from the armature shaft 23 of an electric motor 25. The motor is mounted upon a bracket or support 27, at the forward end of which are also secured members which constitute 85 the frame of casing for the journal bearings.

To deliver oil to the rotary nozzle there is provided a stationary oil delivery member in the form of a sleeve 29 secured to the stationary bearing plate 31 and surrounding the driving shaft 15. The oil delivery member has a reduced end which projects through the open back of the rotary nozzle and has an oil delivery passage 33 connecting with an oil supply pipe 35, 95

by means of which the oil delivered through the pipe is forced to travel through the passage 33 and enters the rear end of the rotary nozzle or cup. Oil thus entering the cup is discharged from the mouth thereof 100 by a centrifugal action. The stationary oil delivery sleeve leaves a relatively small clearance where it enters the rear end of the cup, so that the oil delivered to the cup is prevented from backing up by the lip 105 formed by the bottom of the cup, while it prevents at the same time the use of a solid driving shaft for the cup.

To assist the oil in flowing toward the open end of the nozzle and thereby to main- 110

tain an even delivery and to prevent any tendency of the oil to back up, the nozzle itself is not only slightly tapered or flared from the inner toward the outer end, but there is preferably provided mechanical means for advancing the oil within the nozzle while the latter is being rotated, the same herein comprising radial arms 37 (Figs. 1 and 2) connecting the outer walls 10 of the oil nozzle and its hub 13, such arms being slightly flattened and properly inclined so as to serve as propeller blades to propel and advance the oil delivered to the inner end of the nozzle toward the outer 15 end thereof.

To produce the necessary air supply for the atomizing nozzle 9, a suitable pressure creating device is employed herein in the form of a fan or blower and preferably 20 arranged coaxially with the oil and air nozzles, and also preferably mounted on and driven by the main driving shaft 15. Herein for that purpose, the fan or blower comprises the front and back fan plates 39 and 25 41 provided with suitable blades and carried by the fan spider 43, the latter being keyed or otherwise secured to the drive shaft 15 to rotate therewith. The fan is enclosed within the fan casing 45, which latter is secured to the motor bracket 27 and also affords a support for the bearings 19 for the 30 drive shaft. Adjacent the bearings, the fan casing is provided with air admission passages 47 controlled by a valve or shutter 49, the spider, fan plates and blades also providing suitable air passages so that the air drawn in through the shutter is delivered radially to the end of the casing about the edges of the baffle plate 51, and through 35 passages 53 formed between the baffle plate and the fan casing cover 55, into the rear of the air nozzle 9 and outside of the intermediate sleeve 11. The fan casing cover serves as a support not only for the air nozzle, but for 40 the oil delivery member and the parts connected thereto including the intermediate sleeve 11.

When the motor 25 is operated the drive 45 shaft 15 being rapidly turned, the fan and the oil nozzle are simultaneously rotated, thereby delivering simultaneously a supply of oil and air to the respective oil and air nozzles. The oil is delivered to the supply pipe 35 from a main supply pipe 57, the latter being controlled by a suitable regulating valve 59. The oil may be supplied under a suitable head by means of a pump, but such head is preferably maintained through gravity, by placing the tank (not shown) at 55 a suitable elevation, through the supply pipe 57 under control of the valve 59.

The burner may be, and preferably is, supplied with devices which will simultaneously control the air and the oil so that variation 60 in one will be accompanied by a proper

variation in the other, and this may be secured by simultaneously moving the air valve or shutter 49 and a suitable oil supply valve, but the purpose and manner of such control being fully explained in my aforesaid patent the details are not herein shown.

Should the motor stop or fall below the required speed the air supply would also cease or fall below what is requisite, and the oil nozzle would also fail properly to function. In order automatically to regulate the oil supply under such conditions, and particularly where the oil is fed by means independent of the motor 25, the regulating valve 59 is provided with means whereby the stoppage of the motor or its failure to operate above a certain speed, will insure that the supply of oil is cut off or reduced. For this purpose the valve 59, which may be either a cut-off valve or, if an oil pump is employed, a by-pass valve, is connected (Fig. 5) to an arm 61, the end of which carries a weight 63, the arrangement being such that when the weight is free to drop the arm will be swung down and the valve closed.

The valve controlling weight is normally held (Figs. 1 and 3) in its upper position during the operation of the burner by means of a catch 65 which underlies the bent end of the finger 67 carried by the weight 63. The catch 65 is secured to the end of a shaft 69 mounted to turn in the motor bracket 27 and carrying a segment 71 provided with a peripheral notch 73 and a projecting lug 75. During the operation of the burner, the catch and segment are held in the weight-supporting position (shown in full lines in Fig. 5) by means of the downwardly projecting detent 77 which engages the notch 73. If the detent be lifted, however, the segment is released and will turn to the dotted line position shown in Fig. 3, where the lug 75 abuts against the detent, the catch 65 swinging down to the dotted line position shown, permitting the weight to drop and the valve to close.

The vertical position of the detent is controlled by the speed of the motor. When running at full speed it is allowed to fall to the full line position shown in Fig. 3, where it is effective to retain the weight in a valve-opening position. When the motor stops the detent will lift, allowing the weight to close the valve. For this purpose the detent is carried by the lower end of the slide rod 79 guided for vertical movement in the sleeve 81 and having its upper end secured by the bent portion 83 to a centrifugal device carried by the driving shaft or part connected thereto. Any suitable centrifugal device may be employed, but herein is utilized a well known form consisting of a plate 85 secured to the base of the flexible coupling 21, and on which are pivoted at equi-distant intervals and at the points 86 130

three overlapping segmental or arc-shaped fingers 87, 89 and 91. When the motor is at rest these fingers are drawn radially inward by springs 93, contracting the diameter of 5 the opening which they form, and into which the bent end 83 of the slide rod enters. When the motor is rotated it is driven at full speed, for they move outward on their pivots, into the position shown in Fig. 10 4, enlarging the diameter of this opening and permitting the slide rod to move downwardly.

When the motor is started and attains full speed, but not until then, the weighted 15 arm 61 may be lifted and held lifted through the operation of the catch 65 and the detent 77. At any time the motor stops, however, the detent lifts, the weight drops and the valve closes.

20 Preferably means are also provided whereby the valve 59 may be closed and oil supply shut off automatically in case the fuel back of the burner nozzle catches fire, either through the accumulation of oil beneath the 25 burner or for any other reason. To this end, there is provided a suitable thermally responsive device which at the proper temperature causes the closure of the valve. This may be employed in any desired form, 30 but herein the catch 65 (Figs. 3 and 5) is secured to the shaft 69 by means of a fusible link 93, the latter being fastened at one end to the catch 65 and at the opposite end to the plate 95 which is screwed or otherwise 35 fastened to the squared end of the shaft 69.

In the case of fire, the link 93 will fuse 40 breaking the connection between the catch 65 and the plate 95, releasing the finger 67 and allowing the weight to fall and the valve to close.

While for the purposes of illustration I have herein shown one specific embodiment thereof, it is to be understood that the same is not limited to the details herein shown or 45 to the specific form or relative arrangement of parts illustrated, but that extensive deviations therefrom may be made without departure from the spirit of the invention, and that the same is susceptible of application 50 to widely varying types of apparatus.

Claims:

1. In a rotary oil burner, a rotary oil delivery nozzle, an oil supply conduit, an air nozzle surrounding the oil nozzle, a pressure creating device for delivering air to 55 said air nozzle, a valve for the oil supply operable in the normal usage of the burner to control the oil supply, means tending to move said valve to shut off the oil supply 60 from the oil delivery nozzle, and means including a fusible member to hold said valve in position to maintain said supply.

2. In a rotary oil burner, a rotary oil delivery nozzle, an air supply conduit, an air 65 nozzle surrounding the oil nozzle, a pres-

sure creating device for delivering air to said air nozzle, a motor for rotating the oil delivery nozzle and pressure creating device, a valve for the oil supply, a weighted arm tending to move said valve to shut off 70 the oil supply from the oil delivery nozzle, and a releasable catch device including a fusible member to hold said valve in position to maintain said supply.

3. In a rotary oil burner, a rotary oil delivery nozzle, an oil supply conduit, an air nozzle surrounding the oil nozzle, a pressure creating device for delivering air to said air nozzle, a motor for rotating said oil delivery nozzle and said pressure creating device, a valve for the oil supply, means tending to move said valve to shut off the oil supply from the oil delivery nozzle, a detent to hold said valve in position to maintain 80 said supply, devices to withdraw said detent on the stoppage of the motor and including a fusible member to permit said valve to move to shut off the oil supply on excessive rise of temperature.

4. In a rotary oil burner, a rotary oil delivery nozzle, an air nozzle surrounding the oil nozzle, means for rotating the oil delivery nozzle, and means to shut off the oil supply from the oil delivery nozzle either on the stoppage of the rotation of the oil 95 delivery nozzle or on an excessive rise in temperature.

5. In a rotary oil burner, a rotary oil delivery nozzle located to deliver oil into 100 a combustion chamber, means outside of the combustion chamber for rotating the same, a valve for the oil supply, means tending to move the valve to shut off the oil supply from the oil delivery nozzle, and means including a fusible member to hold said valve 105 in position to maintain said supply or movable to release said valve to permit the shutting off of the oil.

6. In a rotary oil burner, a rotary oil delivery nozzle adapted to deliver oil into 110 a combustion chamber, means outside of said combustion chamber for rotating the same, and means outside of the combustion chamber responsive to an excessive temperature thereat or to a predetermined reduction 115 in speed of said nozzle for shutting off the oil supply from the oil delivery nozzle.

7. In a rotary oil burner, a rotary oil delivery nozzle adapted to deliver oil into 120 a combustion chamber, an oil supply conduit, an air nozzle surrounding the oil nozzle, a pressure creating device for delivering air to said air nozzle, and fusible temporary oil controlling means responsive to an excessive temperature outside of said combustion chamber for shutting off the oil supply to said oil delivery nozzle independently of the supply of air.

8. In a rotary oil burner, a rotary oil delivery nozzle, an air nozzle surrounding 130

the oil nozzle, a pressure creating device for delivering air to said air nozzle, and thermally responsive controlling means for shutting off the oil supply to the oil delivery nozzle, said thermally responsive controlling means being also responsive to a decrease in speed of said nozzle.

9. In a rotary oil burner, a rotary oil delivery nozzle, an air nozzle surrounding the oil nozzle, a pressure creating device for delivering air to said air nozzle, and thermally responsive means for controlling the oil supply to the oil delivery nozzle, said thermally responsive controlling means being also responsive to a decrease in speed of said nozzle.

10. In a rotary oil burner, a rotary oil delivery nozzle, an air nozzle surrounding the oil nozzle, a pressure creating device for delivering air to said air nozzle, and thermally responsive means for controlling the supply of oil irrespective of the control of the supply of air, said controlling means including a valve operable in the normal usage 25 of the burner to control the oil supply.

11. In a rotary oil burner, a rotary oil delivery nozzle, a pressure creating device, a motor for driving the nozzle and the pressure creating device, a motor driven shaft, 30 said nozzle, device and motor shaft being arranged to turn about a substantially horizontal axis, a centrifugal device, a detent member adapted to be lifted when said motor stops, a catch released by the lifting of 35 said member, and an oil valve normally held open by said catch but adapted to close when the catch is released.

12. In a rotary oil burner, a rotary oil delivery nozzle, a motor for driving the 40 same, a centrifugal device including a series of overlapping segments, a detent rod suspended from said segments adapted to be lifted thereby when said motor stops, a catch released by the lifting of said rod, 45 and an oil valve normally held open by said catch but adapted to close when the catch is released.

13. In a rotary oil burner, a rotary oil delivery device, an air delivery device, a pressure creating device for delivering air 50 to said air delivery device, a motor for driving said pressure creating device, an oil controlling valve, means tending to move the valve to shut off the oil supply and means 55 maintained by a predetermined speed by said motor irrespective of the pressure of air for holding said oil controlling valve open.

14. In a rotary oil burner, a rotary oil delivery nozzle comprising a sleeve, means 60 for delivering oil to the inner end of the sleeve, means for rotating the nozzle, an air nozzle surrounding said rotary oil delivery nozzle, and an intermediate sleeve to keep the air out of contact with the oil nozzle periphery, said air nozzle being pro-

longed beyond the intermediate sleeve to provide a narrow annular orifice between the oil delivery nozzle and the air nozzle.

15. In a rotary burner, an oil atomizing cup with a shaft for rotating the same, said cup having an open outer end and an open inner end, a stationary oil delivery member surrounding said shaft and projecting into the open inner end of the cup, said member presenting an oil delivery passage for delivery of oil into the cup, and means for rotating said shaft.

16. In an oil burner, a rotary atomizing cup having an open end and an inner end provided with an opening, a fixed oil delivery member having a portion provided with an oil passage projecting through the open inner end of the cup, and a driving shaft connected to turn said cup and passing through said oil delivery member.

17. In a rotary oil burner, a rotary oil delivery nozzle located to deliver oil into a combustion chamber, means for rotating the oil delivery nozzle, a valve for the oil supply, means tending to move the valve to shut off the oil supply from the oil delivery nozzle, a fusible element, and speed controlled means to hold said fusible element in position to maintain said oil valve open.

18. In a rotary oil burner, a rotary oil delivery nozzle located to deliver oil into a combustion chamber, means for rotating the oil delivery nozzle, a valve for the oil supply, means tending to move the valve to shut off the oil supply from the oil delivery nozzle, a fusible element to hold said valve in position to maintain said supply, and speed controlled means automatically to release said fusible element upon a predetermined reduction in speed.

19. In a rotary oil burner, a rotary oil delivery nozzle, a pressure creating device, a motor for driving the nozzle and pressure creating device, a motor driven shaft, a centrifugal device, a detent member adapted 110 automatically to be lifted by said centrifugal device when the speed of said motor decreases, a catch released by the lifting of said member, and an oil valve normally held open by said catch but adapted to close when the catch is released.

20. In a rotary oil burner, a rotary oil delivery nozzle, a pressure creating device, a motor for driving the nozzle and pressure creating device, a motor driven shaft, a centrifugal device, a detent member adapted automatically to be lifted by said centrifugal device when the speed of said motor decreases, a fusible catch released by the lifting of said member, and an oil valve normally held open by said catch but adapted to be closed when the catch is released or fused.

21. In an oil burner, a rotary atomizing cup having an open outer end and a bottom 120

- provided with an opening, a fixed oil delivery member having a portion provided with an oil passage projecting through the open end of the cup and including a lip 30
- 5 constituting the terminus of said oil passage and a driving shaft connected to turn said cup and passing through said oil delivery member.
22. In an oil burner, a rotary atomizing 10 cup having a bottom provided with an opening, a fixed oil delivery member having a portion provided with an oil passage projecting through the open bottom end of the cup and including an annular lip constituting 15 the terminus of said oil passage and a driving shaft connected to turn said cup and passing through said oil delivery member.
23. In a rotary oil burner, a rotary oil delivery nozzle, a pressure creating device, a 20 motor for driving the nozzle and the pressure creating device, a motor driven shaft, a centrifugal device, a detent member adapted to be lifted by said centrifugal device when said motor stops, a pivoted catch released by the lifting of said member, an oil valve normally held open by said catch but adapted to close when the catch is released and means for effecting the interlocking of 25 said detent member and said pivoted catch
- including an elongated notch to receive said detent and permit manual pivotal movement of said catch relatively to said detent to release said valve.
24. In a rotary oil burner, a rotary oil delivery nozzle, an oil supply conduit, an air 35 nozzle surrounding the oil nozzle, a pressure creating device for delivering air to said air nozzle, a freely operable oil supply valve, means tending to move said valve to shut off the oil supply from the oil delivery 40 nozzle and means including a fusible member to hold said valve in position to maintain said supply.
25. In a rotary oil burner, a rotary oil delivery nozzle, an oil supply conduit, an air 45 nozzle surrounding the oil nozzle, a pressure creating device for delivering air to said air nozzle, a freely operable fuel supply valve, means tending to move said valve to shut off the oil supply from the oil delivery 50 nozzle, a fusible member to hold said valve in position to maintain said supply and speed responsive means for supporting said fusible member in its valve holding position.
- In testimony whereof I have signed my name to this specification.
- ARTHUR H. BALLARD.
